DIRECTIONAL ELECTROSTATIC SPEAKER ASSEMBLY

John P. Kuehn, Huntington, N.Y., assignor to Pickering Associates, Inc., Oceanside, N.Y., a corporation of New York

Application October 18, 1956, Serial No. 616,741

1 Claim. (Cl. 179—147)

This invention relates generally to electrostatic speakers and more particularly relates to a directional electrostatic speaker assembly.

An electrostatic speaker is a device which translates electrical signals into sound waves. An acoustical element such as a diaphragm is used which acts with a fixed plate to form a condenser. Variations in the output wave in the electrical system will cause the diaphragm to move in synchronism therewith, thereby establishing a sound wave.

When an electrostatic speaker is utilized the sound radiation is highly directive. This is especially so at the higher frequencies. And in those systems employing a low frequency speaker and a high frequency electrostatic speaker, it is often difficult to direct the sound waves of the high frequency speaker for maximum enjoyment.

In systems where an electrostatic speaker is employed the direction of the sound waves with respect to the physical position of the listener can have a large effect on the enjoyment resulting to the listener. Also, many persons find greater listening pleasure when they can direct the sound waves in order to take maximum advantage of the acoustics in the room. Often listeners employ more than one speaker and desire to direct the sound waves from the various speakers in such manner that the sound waves cooperate and complement one another.

In order to properly direct the sound waves, an electrostatic speaker must be designed so that the highly directional characteristics of the waves can be utilized to give maximum enjoyment to the listener and avoid undesirable results.

The invention herein disclosed has as its main object the provision of a directional electrostatic speaker with which highly directional sound waves can be properly distributed and dispersed.

Another object of this invention is to provide a directional electrostatic speaker with which sound waves can be directed in conformity with the physical position of the listener and the room architecture.

A further object of the invention is to provide a directional electrostatic speaker assembly which utilizes few parts and requires a minimum amount of time and effort to manufacture and assemble.

The construction of the directional electrostatic speaker is described herein with reference to the drawings, in which:

Fig. 1 is a front elevational view of a directional electrostatic speaker constructed in accordance with the teachings of this invention with a portion thereof shown in section;

Fig. 2 is a front perspective view of the speaker shown in Fig. 1 with the speaker slightly pivoted about a horizontal axis;

Fig. 3 is a partially sectional elevation taken along the line 3—3 in the direction of the arrows indicated in Fig. 1; and

2

Fig. 4 is a side view of the electrostatic speaker shown in Fig. 1 with the speaker pivoted slightly about its horizontal axis and a portion thereof shown in section.

The speaker shown in the figures consists of a plastic frame composed of arcuate top and bottom segments designated by the numerals 10 and 11, respectively. These segments are identical and joined by elongated side members 12 and 13 which are of rectangular cross-section and also constructed of plastic material. As seen in the figures, one end of member 10 and one end of member 11 are joined by member 12 and the remaining ends of members 10 and 11 are joined by member 13.

It should be noted that although members 10, 11, 12 and 13 have been described as plastic members, they can be constructed or formed from wood or any other suitable material.

Screen 14, which is seen in Fig. 4, is one of two identical acoustically transparent metal screens 14 and 15. These screens are preferably made of woven galvanized iron wire.

Each of the screens is flocked with fibers of cotton, rayon, fiber glass or other dielectric material. The flocking on screen 14 is designated generally as 16 while the flocking on screen 15 is designated generally as 17.

Acoustical element 18 is maintained in position between the flocking 16 and 17. This acoustical element can be any diaphragm which is suitable for this purpose and the precise manner in which diaphragm 18, the flocking and the transparent screens are mounted is described and claimed in a co-pending application, Serial No. 545,875, entitled "Electrostatic Speaker," which was filed in the United States Patent Office on November 9, 1955 and which is assigned to the same assignee as is this application.

For the practice of my invention, it is not necessary that flocked screens be used, nor is it necessary that the precise arrangement shown in the co-pending application referred to above be utilized and the arrangement described and claimed in the above-mentioned co-pending application is referred to herein for illustrative purposes only.

Screens 14 and 15 are covered with acoustically transparent ornamental screens 19 and 20, respectively, as shown.

My invention resides in the shape of the speaker as determined by the arcuate segments and the assembling or mounting of the same to a base. As seen in the figures, the external appearance of the speaker is such that its front is convex while its rear is concave.

The convex front which is designated as 19a, serves to radiate the sound waves or disperse them in a plane perpendicular to pillar 21 which extends upward through bottom segment 11 and which is rigidly connected at its end to top segment 10. Pillar 21 is cylindrical member having an axial internal cylindrical opening throughout its length. An identical pillar 22 extends parallel to pillar 21 through segment 11 and is connected to the top segment at the other end of the speaker.

Pillars 21 and 22 serve to support the speaker above an underlying surface as shown. Also a swivel mounting is employed which connects these pillars to base 23, which is a wooden rectangular member. The base member can be any configuration or material desired. An end of pillar 21 is shown in Fig. 3 where a detailed view of the swivel mounting is also shown.

Sleeve 24 is attached to the lower end of pillar 21. Sleeve 24 is also a cylindrically hollow member and has a large opening 25 with an internal diameter approximately equal to the external diameter of pillar 21 and is mounted thereon in a press fit. Opening 25 projects into a smaller diameter opening 26 which has an internal diameter approximately equal to the internal diameter

of the opening in pillar 21. The portion of sleeve 24 through which the smaller diameter hollow extends is externally threaded at 26a.

Spring housing 27 has cylindrical openings of various diameters extending therethrough and one end of member 27 is internally threaded at 27a so that member 27 can be joined with sleeve 24 by cooperation of threads 26a and 27a. A portion of the hollow within member 27 is formed to enclose helical compression spring 28, which sets within. The spring as mounted yieldingly urges ball seat 29 downwardly against ball 30, which is attached to base 23 by means of externally threaded tail 31, which passes through the base and is fastened thereto by nut 32. As seen in Fig. 3, a portion of the base is recessed so that nut 32 will not interfere with the surface upon which base 23 is placed.

Ball seat 29 which is a washer-like member has a cylindrical opening extending therethrough and rests atop ball 30. Adjustment member 33 has a ball seat portion 34 formed therein which encompasses the lower periphery of ball 30 and an upper internally threaded portion 33a which can cooperate with external threads 27b at the lower end of spring housing 27.

As pointed out above, each of the members which cooperates to maintain pillar 21 in attachment with base 23 has a cylindrical opening extending therethrough. The purpose of this is to enable cable 34 to extend upwardly into the speaker for attachment with the diaphragm or acoustical element. The other end of cable 34 which is not shown is attached to the output of the electrical system of the device. Pillar 22 is maintained in attachment with base 23 in the same manner as is pillar 21.

As shown in Fig. 3, pillar 21 is free to rotate about any horizontal axis through ball 30. Likewise, pillar 22 is free to rotate about any horizontal axis through the ball associated with it. However, since pillars 21 and 22 are connected to rigid bottom segment 11, they are restricted to rotation about the single horizontal axis which passes through the balls associated with them. An imaginary horizontal axis of rotation is shown as the line X—X in Fig. 2.

The front of the speaker as mentioned before is convex. Therefore, sound radiating therefrom is dispersed in a plane which is parallel to the vertical axis of the front of the speaker. This axis is shown in Fig. 2 as the line Y—Y.

Utilizing the swivel mountings of pillars 21 and 22 the sound waves radiating from the speaker can be directed in a vertical plane about the axis X—X so that with my speaker sound waves are dispersed in a horizontal plane perpendicular to the vertical plane of the speaker because of the convex configuration of the front of the speaker and can be dispersed in a vertical plane perpendicular to the axis of rotation of pillars 21 and 22.

The speaker is shown in Fig. 2 pivoted slightly forward so that the sound radiating therefrom is directed downwardly as well as radially. A side view of the speaker in substantially the same position is shown in Fig. 4.

Adjustment member 33 when threaded upon spring housing 27 applies friction force between ball 30 and ball seat 29 due to the force of spring 28 so that the pillar associated therewith is maintained in position and thus allows the speaker to be maintained in position at an angle about the X—X axis. With this assembly, the electrostatic speaker can be adjusted about the horizontal axis and maintained in the position desired.

Also, since ball and socket joints are used, aligning problems in assembly are greatly reduced.

Thus, among others, the several objects of the invention as specifically aforementioned are achieved. Obviously, numerous changes in construction and rearrangement of parts may be resorted to without departing from the spirit of the invention as defined by the claim.

I claim:

A directional electrostatic speaker assembly including in combination an acoustical member, a front surface of said acoustical member convex about a vertical axis, a rear surface of said acoustical member concave about a vertical axis, a rigid bottom surface of said acoustical member, a flat base, a support member rigidly connected at one end to said bottom surface and perpendicular thereto, a second support member spaced from said first support member and rigidly connected at one end to said bottom surface and perpendicular thereto, a pivotal connection of the remaining end of said first support member to said base, a second pivotal connection of the remaining end of said second support member to said base, an axis of rotation formed by the pivotal connections of said support members, said rigid members spaced from one another and parallel with one another for rotation about said axis of rotation whereby the position of said acoustical element with respect to said base can be changed solely by rotation of said support members about said axis and means associated with each of said pivotal connections for maintaining its respective support member in a fixed position.
